UNITED STATES PATENT OFFICE

RICHARD WEINGART, OF NEW YORK, N. Y., ASSIGNOR TO EVEREADY PEN COMPANY, INC., OF NEW YORK, N. Y., A CORPORATION OF NEW YORK

FOUNTAIN PEN

Application filed September 5, 1930. Serial No. 479,837.

This invention relates to fountain pens, and has for its general object to provide an improved adjustable barrel construction whereby at will to completely incase the writing nib within the barrel construction.

One object of the invention is the provision of an incasing covering consisting of a pair of cooperative relatively adjustable barrels, each provided at the nib end of the pen structure with a plug and a seat opening, the improvements relating especially to a construction in which, when the nib is incased, the plug of each barrel will occupy a position within the seat opening of the other barrel and in such relation that the outer surfaces of the two interseated plugs will be in smooth flush relation.

According to a feature of my invention, the plug and seat parts are constructed and arranged to interfit so as to produce a tight sealing engagement and thus prevent any leakage of ink from the interior of the structure. For the purpose of producing a non-leak seal, the plug and seat parts are of a substantial thickness or depth, and the barrels are so connected that in order to effect the seating and unseating of the plugs, one of the barrels must be given a definite lengthwise or longitudinal movement relatively to the other. This relative longitudinal movement is important, inasmuch as it makes provision not only for a liquid-tight seal, but for a movement of an extent sufficient to prevent any contact between the plug parts during relative turning movement of one of the barrels. By this arrangement, a deposit of ink from or around the nib upon the inner faces of the parts cannot be transferred to the outer surface of the outer barrel. With my improved construction, any leakage of ink cannot reach or be carried to, the exposed surface of the incasing barrel. The fingers and clothing, therefore, cannot become soiled or daubed with ink through handling or carrying the fountain pen structure while the parts thereof are in closed relation.

Another object of the invention is the provision of a construction of the character described, in which the cooperating parts, on manual circular movement to a given posi-

tion, will be automatically closed and then be maintained in tightly closed relation by an expansion spring. Owing to this provision, the liquid-tight seal is not impaired or broken by jarring the fountain pen structure.

55

A further object of the invention is the provision of a construction of the character described, in which the stock for carrying the writing nib and for containing the ink nib can be readily and conveniently removed for filling or cleaning purposes.

Other objects and advantages of the invention will appear hereinafter.

The invention resides in the improved fountain pen structure, and in the form, construction and relative arrangement of its several parts, as will be hereinafter more fully described, illustrated in the accompanying drawings, which forms a material part of this application, and subsequently incorporated in the subjoined claims.

65

In the drawings, wherein I have illustrated a preferred embodiment of the invention as reduced to practice, and in which similar reference characters designate corresponding parts throughout the several views:

Figure 1 represents a central longitudinal sectional view through my improved fountain pen, the parts being shown in the relative positions they occupy when the writing nib is incased, and some of the parts being illustrated as partially broken away;

Fig. 2 is an end elevation, looking toward the right hand end of Fig. 1;

Fig. 3 is a view similar to Fig. 1, but showing the inner barrel and pen stock withdrawn to position for effecting the rotary movement;

Fig. 4 is a cross section taken on the line 4—4 of Fig. 3;

Fig. 5 is another view similar to Fig. 1, but showing the parts in the relative positions they occupy when the writing nib is protruded;

Fig. 6 is a cross section taken on line 6—6 of Fig. 5;

Fig. 7 is a sectional view, showing a modification of a detail; and

Fig. 8 represents a sectional view on a larger scale showing the shoulder and groove connections for effecting a tight seal.

100

Referring with more particularity to the accompanying drawing, the numeral 10 designates the elongated stock or body part of the pen for containing the supply of ink, and 5 which at one end thereof is equipped with a writing nib 11. The stock or body and connected writing nib may be of any suitable or approved form of construction.

My invention, in its preferred form of construction as illustrated in the accompanying drawing, comprises an adjustable covering for incasing the body and nib and consists of inner and outer barrels 12 and 13, the inner barrel being adjustably fitted upon the body 15 while the outer barrel is adjustably fitted upon the inner barrel.

At the nib of the pen structure, the outer barrel 13 is made with an end consisting of a semi-circular plug 14, a semi-circular flange 20 15 in continuation of the plug, inturned from the end of the barrel, and a semi-circular seating opening 16 between the plug 14 and flange 15 as best shown in Figs. 2 and 8. The end edge of the plug 14, where it defines the 25 diametrical side of the seating opening 16, is by preference inwardly beveled as shown at 17.

The corresponding end of the inner barrel 12 is made with plug and seating parts 30 adapted to interfit with the plug and seating parts of the outer barrel. Thus it will be seen from an inspection of the drawing that the inner barrel has a semi-circular plug 18 shaped to fit snugly in the seating opening 35 16 of the outer barrel, and that it also has a seating opening 19 for receiving the plug 14 of the outer barrel, said plug 18 being beveled at 20 in conformity with the beveled edge 17 of the plug 14. Preferably as shown, 40 the plugs 14 and 18 are of equal thickness; and when they are in interfitting engagement with the plug 18 in the opening 16 and with the plug 14 in the opening 19, the outer surfaces or faces of the plugs will lie in a smooth 45 and flush relation, as best shown in Fig. 8. When the plugs are inter-engaged, as shown in Fig. 8, they form a liquid-tight seal against leakage of ink from the interior of the pen structure to the exterior thereof. 50 For further effecting a liquid-tight sealing engagement, a groove 21 is provided around the plug 14 at the inner side thereof and along the inner periphery of the barrel 13. This groove has a tapering edge 21'. The 55 free end edge 22 of the inner barrel is shaped and tapered for seating in the tapered groove 21. The flange 15 presents at its inner side a shoulder 23 with which interfits a corresponding shoulder 24 formed for the purpose 60 on the plug 18 of the inner barrel, the said interfitting shoulders 23 and 24 lying in a plane common to the plane in which the end edge 22 of the inner barrel contacts with the bottom of the groove 21. Through this 65 arrangement of interfitting plug and seating

parts, I provide a tight seal against the passage to the outside of the pen structure of any ink which may leak from around the writing nib 11. The plug and seating parts are relatively deep and according to an important feature of my invention, they are engaged and disengaged by moving either the outer or inner barrels in a direct lengthwise direction 70 longitudinally of the pen structure.

In the present embodiment, the outer barrel is somewhat longer than the inner barrel and a coil expansion spring 25 is imprisoned between the rear end of the inner barrel and an inturned flange 26 at the rear end of the outer barrel, said spring surrounding the body 10 of the pen. This spring normally urges the inner barrel into that position in which the plug and seating parts of the two barrels will be firmly interengaged and sealed. The outer barrel is provided with three communicating slots 27, 27', and 27'', the slots 27 and 27'' extending longitudinally of the barrel at opposite sides thereof and communicating at their rear ends at right angles with the slot 27' which curves around the barrel for a distance of substantially 80 180°. The inner barrel 12 is provided with two communicating slots 28 and 28', the former extending longitudinally of this barrel and being of a length substantially equal to the slot 27, while the slot 28' curves around this barrel and is of a length substantially equal to the slot 27'. Said slots 28 and 28' communicate at right angles as shown. The slot 27'' is relatively short, its purpose being 85 to enable relative longitudinal displacement of the two barrels for a distance sufficient not only to separate the plug and seating parts but to provide a substantial space between the outer face of the plug 18 and inner face of the plug 14, as best shown in Figs. 3 and 5. The purpose of this spacing, as will presently appear, is to prevent at all times any contact between the outer face of the plug 18 and the inner face of the plug 14, 90 so that ink, which may be deposited upon the inner face of the plug 14, cannot be transmitted to the outside of the pen structure.

Surrounding the outer barrel 13 for relative adjustment thereon is a ring or sleeve 95 29 which carries an inwardly extending pin 30 capable of working in the slots 27'', 28, 27' and 27. This pin is removably entered in a circular opening 31 provided for the purpose in the stock or body 10. By this provision the ring 29 and body 10 can together be maintained stationary or moved, according to the manner in which the parts of the arrangement are manipulated. The outer barrel 13 has an inwardly projecting 100 pin 32 capable of working in the slots 28 and 28'. 105

When the body and writing nib are incased by the barrels with the plug and seating parts of the barrels seated and sealed in interfitting 110 115 120 125 130

arrangement, as shown in Fig. 1, the ring 29 may be freely moved to the left so as to move the body and inner barrel to the left, forcing compression of the spring 25. This movement to the left not only unseats the plug 18, but spaces it a considerable distance from its seat and at the same time brings the pin 30 into alignment with the circular slot 27', and it further brings the circular slot 28' into alignment with the pin 32. The several parts are thus brought into position for the rotary operation. The unseating operation and consequent alignment of the pins 30 and 32 with their respective circular slots may be accomplished with equal facility in another way, namely, by holding the ring 29 and moving the outer barrel to the right, which operation results in compressing the spring 25 and in aligning the slots 27' and 28' with their respective pins 30 and 32.

Having moved the parts into the relative positions shown in Fig. 3, the next operation (following the mode of operation illustrated in the drawing) is to grasp the ring 29 and hold it stationary while turning the outer barrel 13 180° so as to bring the plug 14 in front of the plug 18 and the seat opening 17 in alignment with the seat opening 19. Since the body 10 and ring 29 are connected by the pin 30, the former remains stationary with the ring, while the pin 32, attached to the outer barrel 13, moves through the circular slot 28'. The outer barrel, in thus being rotated, turns between the ring 29 and the inner barrel 12 and its circular slot 27' turns on the pin 30. This turning operation brings the longitudinal slot 27 in the outer barrel into registry with the longitudinal slot 28 in the inner barrel. Manifestly, this turning operation may be accomplished in another way, namely, by holding the outer barrel 13 stationary while turning the ring and consequently the inner barrel and body 180°, so as to bring the longitudinal slot 28 of the inner barrel into registry with the longitudinal slot 27 of the outer barrel.

When the longitudinal slots 27 and 28 of the inner and outer barrels have been brought into registry, the seat openings 17 and 19 will be in registry, so that by moving the ring forwardly (or the outer barrel rearwardly) the writing nib 11 will be projected through the two aligned seat openings 17 and 19 into position for writing as shown in Fig. 5.

To incase the writing nib, it is necessary only to reverse the operations. The pin 30 is moved to the rear of the longitudinal slots 27 and 28, that is to say, to the position in which it will enter the circular slot 27'. Manifestly, this may be accomplished either by moving the ring rearwardly or by moving the outer barrel forwardly. The necessary circular operation is then effected, either by rotating the ring or the outer barrel through the distance permitted by the circular slots

27' and 28', so as to bring the pin 30 into the slot 27' and the pin 32 into the slot 28. Thereupon the compression spring 25 will automatically force the relative longitudinal movements of the parts to seat and seal the plugs 18 and 14 in their respective seating openings as shown in Fig. 1.

In order to permit the removal of the body 10 with its writing nib for filling or cleaning purposes, the pin 30 is mounted for retraction, at will, from the circular opening 31 in the body. To this end, the pin 30 is carried at or near the free end of a spring clip 33 (Fig. 6) which forms a part of or is suitably attached to the ring 29. The outer or free end of this spring clip is preferably beveled as at 34 so as to receive thereunder the finger nail or any suitably pointer instrument, whereby to be lifted outwardly from the ring so as to lift the pin 30 from the circular opening 31. When the pin has thus been withdrawn from the opening 31, the body 10 with the writing nib attached may be withdrawn. Before withdrawing the pin 30 from the opening 31, it is best to move the ring into the position shown in Fig. 3, in which position the rear end of the body 10 will project, for ready seizure by the fingers, beyond the corresponding end of the outer barrel.

In Fig. 7 I illustrate a modification in the mode of providing a liquid-tight seal between the free edges of the plugs 18 and 14. The cooperating free edges of the plugs, instead of being beveled or tapered, may be provided with interlocking tongues and grooves 35 and 36, capable of being engaged and disengaged under lengthwise movement of one of the barrels in a direction longitudinally of the pen structure.

While I have shown in the present instance a preferred manner of connecting the body and outer and inner barrels, it is to be understood that in the broad scope of my invention, these connections may be located and spaced in any desired manner and still be within the scope of my invention.

The terms and expressions employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

I claim:—

1. A fountain pen the body and nib of which are provided with a covering consisting of a pair of barrels connected for relative longitudinal movement, each of said barrels at the nib end of the pen including a plug and a seat opening, the plug of each barrel being shaped to fit into and effect a seal with the seat opening of the other bar-

rel, said plugs being insertable in and removable from the seat openings on longitudinal movement of one of the barrels.

2. A fountain pen the body and nib of which are provided with a covering consisting of a pair of barrels, a connection between the barrels and body arranged to allow first a definite longitudinal movement and then a definite circular movement of one of the barrels, each of said barrels at the nib end of the pen including a plug and a seat opening, the plug of each barrel being shaped to fit into and effect a seal with the seat opening of the other barrel, said plugs being insertable in and removable from the seat openings on the definite longitudinal movement of the barrel, said seat openings being shaped so as to be aligned one with the other to produce an outlet opening for the nib on the definite circular movement of the barrel.

3. A fountain pen the body and nib of which are provided with a covering consisting of a pair of barrels, a connection between the barrels and body arranged to allow first a definite longitudinal movement and then a definite circular movement of one of the barrels, each of said barrels at the nib end of the pen including a plug and a seat opening, the plug of each barrel being shaped to fit into and effect a seal with the seat opening of the other barrel, said plugs being insertable in and removable from the seat openings on the definite longitudinal movement of the barrel, said seat openings being shaped so as to be aligned one with the other to produce an outlet for the nib on the definite circular movement of the barrel, means to afford and maintain a locking connection between the barrels when the seat openings are aligned, and means associated with said connection whereby to move the body and nib relatively to the barrels to project the nib out of said outlet.

4. A fountain pen, having a body and a nib, characterized by including outer and inner barrels for incasing the body and nib, said barrels including at the nib end of the pen, interfitting plug and seat parts adapted for seating and unseating action on movement of one of the barrels lengthwise of the pen, a ring loosely fitting the outer barrel and connected with the body by a pin, both of the barrels having slots therein in which the pin works, the slot in the outer barrel including two longitudinal portions connected by a curved portion, the slot in the inner barrel including a longitudinal portion with a curved portion at one end, a pin fixed in the outer barrel engaging the slot in the inner barrel, said slots and pins providing for the movement of one of the barrels longitudinally to unseat the plugs and then circularly to align the seats, said fixed pin in the outer barrel provided for locking the barrels to-

gether subsequently to the circular movement and the ring with its pin providing for movement of the body relatively to the locked barrels for projecting the nib through the aligned slots.

5. A fountain pen the body and nib of which are provided with a covering consisting of a pair of barrels connected for relative longitudinal movement, each of said barrels at the nib end of the pen including a plug and a seat opening, the plug of each barrel being shaped to fit into and effect a seal with the seat opening of the other barrel, and a spring imprisoned between the barrels and normally tending to move them in a longitudinal direction to insert and seal the plugs in the seat openings, said spring being compressible between the barrels to permit removal in a longitudinal direction of the plugs from the seat openings.

6. A fountain pen, having a body and a nib, characterized by including a pair of barrels for incasing the body and the nib, said barrels including at the nib end of the pen interfitting plug and seat parts adapted for seating and unseating action on movement of one of the barrels lengthwise of the pen, said seats being adapted for alignment to provide an opening for the nib on movement of one of the barrels circularly of the pen, pin and slot connections between said barrels to control said longitudinal movements and said circular movement, each independently of the other, one of said pins being connected with the body to allow relative longitudinal movement between the barrels and the body for the projection of the nib out of the opening provided by the aligned seats, and a resilient member imprisoned between the barrels.

7. In a fountain pen, embodying an ink containing body with a writing nib, a pair of incasing members for said body and nib, provided at the nib end of the pen with interfitting plug and seat parts, said seat parts including seat openings for the plugs and said plug and seat parts being constructed and arranged for seating and unseating action on movement of one member in a direction lengthwise of the other of the members, means by which to move one of the members lengthwise of the other of the members, means by which to rotate one of the members to align said openings for the projection of the nib therethrough, and means by which to move said body lengthwise and independently of said members.

8. In a fountain pen, embodying an ink containing body with a writing nib, inner and outer incasing members for said body and nib, provided at the nib end of the pen with interfitting plug and seat parts, said plug and seat parts being constructed and arranged for seating and unseating action on movement of one of the members in a

direction lengthwise of the other of the members, a connection between said members and body to afford an engagement between them while permitting relative movement of one of the members in a lengthwise direction with respect to the other of the members, and a connection, other than the first connection, between said members, arranged to allow relative rotation of one of said members and body in unison and independently of the other of the members.

In testimony that I claim the foregoing as my invention, I have signed my name hereto.

RICHARD WEINGART.
